SAFETY RAZOR

Nicholas Testi, Boston, Mass., assignor to Gillette
Safety Razor Company, Boston, Mass., a cor-
poration of Delaware

Application October 27, 1943, Serial No. 507,773

7 Claims. (Cl. 30—70)

This invention consists in improvements in safety razors facilitating the presentation to the razor of fresh sharp blades while protected by a wrapper or envelope which it is desired to remove only after the blade has been positively and completely located in its shaving position.

The shaving edge of a thin safety razor blade is brought to such a high degree of fineness that it is extremely delicate and its keenness is likely to be destroyed if the edge is accidentally drawn across any part of the razor or the blade magazine or even the blade wrapper preparatory to shaving. Great care and considerable skill is required ordinarily on the part of the user to extract such a blade from its wrapper and present it safely in its shaving position without damage to its edge. The present invention deals with blades of a type which may be protected at the time of manufacture by being enclosed in a paper wrapper. This wrapper overlaps and safeguards the sharp edge or edges of the razor blade and must be removed to make the edge accessible for shaving. We contemplate a safety razor so organized that the wrapped blade may be delivered directly thereto in its final shaving position and temporarily held as thus positioned while the user has only to strip the wrapper from the blade and withdraw it from the razor, all this being effected without danger and even without the possibility of touching the keen cutting edge of the blade.

To this end an important feature of the improved safety razor consists in pivotally mounting either the cap or guard member and providing it with a projection for engaging a perforated blade inserted between the two members. Preferably and as herein shown spring means are provided for rocking the pivoted member so that its projection engages and holds the blade against longitudinal movement, and it is while so engaged that the user may grasp and conveniently strip the cover from the blade. Any desired means may be provided for rocking the pivoted razor member in opposition to such spring action for releasing the blade and as herein shown such means are conveniently provided in the shape of a stud which projects freely through the opposed blade-clamping member where it may be readily manipulated by the user preparatory to presenting a fresh or unused covered blade to the razor or in removing a used blade therefrom.

These and other features of the invention will be best understood and appreciated from the following description of a preferred embodiment thereof, selected for purposes of illustration and

shown in the accompanying drawing, in which—
Fig. 1 is a view in perspective of a complete
razor showing a blade in its position of presenta-
tion.

Fig. 2 is a similar view showing a blade clamped
in shaving position;

Fig. 3 is a fragmentary view similar to Fig. 2
but as seen from a different angle;

Fig. 4 is a view in longitudinal section on an
enlarged scale and corresponds to Fig. 1 except
that a section is broken from the handle;

Fig. 5 is a view in perspective showing the parts
of the razor and blade in exploded relation; and

Fig. 6 is a view of the razor in longitudinal sec-
tion and on an enlarged scale corresponding to
Fig. 2.

The invention is not limited to safety razors of
any specific type, and while it is herein shown as
embodied in a razor of the "Gillette" type, with
suitable modification it is capable of general ap-
plication. The illustrated razor includes in its
structure a guard or blade-supporting member
10 of rectangular contour having a blade-sup-
porting face shouldered longitudinally and pro-
vided at its edges with downturned guard flanges
11. The blade-supporting face is centrally de-
pressed in the form of a diamond-shaped recess
12 and, the wall of the recess is centrally per-
forated to receive the handle of the razor and
slotted at its opposite ends to receive the blade-
locating rib of the cap.

The handle comprises a tubular barrel 13 shoul-
dered so that its upper end may be inserted
through the perforation of the guard and riveted
35 in place upon the bottom of the recess 12 thus
permanently uniting the barrel of the handle and
the guard member. The barrel 13 of the handle
contains in its lower end an elongated tubular nut
14 shouldered and having a knurled head which
40 extends at all times below the end of the barrel
and being threaded internally in its upper end to
receive the threaded spindle 22 of the cap.

The cap 16 corresponds in contour to the guard
10 except that it is narrower and has a concave
45 blade-engaging face which extends over the lon-
gitudinal shoulders of the guard thus clamping
the blade in a position of transverse curvature
when the cap and guard are drawn together by
rotating the nut 14. In both corners at one end
50 of the cap are provided downwardly projecting
pins 17 and at the other end the cap has a shallow
recess 18 to facilitate grasping the end of a cov-
ered blade beneath the cap. It is provided cen-
trally with a narrow blade-locating rib 19 from
55 which projects a short flat-sided stem 20 bevelled

or cut away at one side of its end surface. One end of the rib 19 is provided with a downwardly extending projection 15 of the same width as the rib which is arranged to pass freely into the slot at one end of the diamond-shaped recess 12 of the guard member. This projection 15 serves the purpose of a guide or pilot for directing an open-end blade properly when the blade is presented between the cap and guard members, by passing into the open end of the blade slot. The projection 15 provides an unbroken wall between the blade-engaging faces of the cap and guard which must be straddled by the two sides of the blade as the latter is advanced endwise between them. The cap 16 is also provided at one side of the stem with a circular boss 21 into which the rib merges. This boss is substantially wider than the rib and extends symmetrically on both sides thereof.

The stem 20 of the cap is arranged to be fitted into the forked upper end of a spindle 22 which is threaded at its lower end for engagement with the upper end of the tubular nut 14 as shown in Fig. 4. A pivot pin 23 extends through the forks of the spindle and the stem 20 thus permitting the cap to rock freely on the spindle. The upper end of the handle barrel is chambered to receive the upper end of the spindle 22 and the stem 20 with substantial clearance and also to receive with clearance a loose collar 24 and a compression spring 25, both of which surround the spindle 22. In assembling the razor parts a stud 26 is inserted through the slot at the other end of the depression 12 in the guard member from the slot occupied by the rib extension 15 and the shank of this stud is permanently fastened in the boss 21 of the cap. The shank of the stud is no thicker than the rib 19 and so of itself offers no obstruction to the presentation of a blade but passes freely through the slot thereof. A stop screw 27 is inserted in the lower end of the spindle 22 in position to engage the internal shoulder in the upper end of the nut 14 and prevent complete disengagement of the cap and guard while permitting a limited separation sufficient to admit a blade between them.

The razor above described is adapted particularly for use with a double-edged blade of the well-known type shown in Fig. 5. This blade is recessed and shouldered in each corner to provide elongated centrally disposed unsharpened end portions. It is slotted longitudinally and its slot extends out through one end portion of the blade making it an open-ended blade. The blade is provided with a protective cover 31 of sheet material which is folded so as to protect the sharpened cutting edges of the blade and to extend in the form of a folded cuff beyond the solid end thereof.

A protected blade of this general type is shown in U. S. Patent No. 2,194,281, March 19, 1940, Gustafson, to which reference may be had for further details of the protective cover. It will be noted, however, that this extends on both sides of the blade beyond its sharpened cutting edges and is cut away centrally fully to expose the blade slot.

The slot of the blade 30 is designed to receive the blade-locating rib 19 of the cap and includes a transverse enlargement or aperture 32 shaped to fit the boss 21. This boss it will be understood is of greater diameter than the width of the slot of the blade so that the blade cannot be slipped fully into shaving position upon the guard mem-

ber except when the boss 21 is retracted above the path of movement of the blade.

The flat stem 20 is slightly wider than the diameter of the spindle 22 so that its long side 5 is engaged by the loose collar 24 located directly beneath it on the spindle. The length of the spring 25 and depth of the recess in the upper end of the razor handle are such that when the tubular nut 14 is rotated to its limiting position 10 the cap 16 is drawn down into firm clamping engagement with the blade which has been presented between the cap and guard members of the razor and the spring 25 is tightly compressed within its recess. This is the condition 15 of the razor as shown in Fig. 6 and it will be noted that the head of the stop screw 27 is spaced a substantial distance below the shoulder in the upper end of the tubular nut 14. This distance represents the amount of separation permitted 20 between the cap and the guard when the nut 14 is turned reversely until it is again limited in its rotation, this time by the head of the screw 27 as shown in Fig. 4.

As the nut 14 is turned reversely and the 25 spindle 22 permitted to rise, the action of the spring-pressed collar 24 upon the right side of the stem 20 is to rock the cap 16 in a counterclockwise direction about the axis of the pivot pin 23. This tends to hold the left-hand end of 30 the cap down against the guard, thus maintaining the boss 21 engaged in the perforation 32 of the blade 30. The blade is thus locked against longitudinal movement and can only be released by upward pressure on the part of the user 35 against the head of the stud 26. This overcomes the action of the spring 25 and rocks the cap, lifting the boss 21 out of the perforation 32 and permitting the blade to be freely withdrawn toward the right as seen in Fig. 4. In this movement of withdrawal the shank of the stud 26 40 passes freely out of the open end of the blade slot.

From the foregoing explanation the operation 45 of presenting a protected blade to the razor will be easily understood. Having loosened the nut 14 so that the cap occupies the position shown in Fig. 4, that is to say, with its right-hand end lifted and its left-hand end depressed against the guard, the user may introduce the open end 50 of a protected blade into the space which the action of the spring 25 provides for it at the right-hand end of the razor. In initiating the presentation of the blade the latter is guided by the pilot projection 15 at the right-hand end of 55 the rib 19. With the razor parts in this position, however, the movement of the blade is soon obstructed by engaging the boss 21. Accordingly, the user must press upwardly upon the head of the stud 26 to rock the cap and retract the 60 boss above the surface of the blade. When this has been done the inward movement of the blade may be continued until the shoulders at its advancing end bring up against the pins 17 of the cap, the pins being spaced to engage the side 65 edges of the shoulders at the open end of the blade and positively prevent spreading thereof when the blade is being clamped. The blade is thus located in the proper longitudinal position for shaving and when the stud 26 is now released 70 the spring 25 acts to rock the cap and carry the boss 21 into the aperture 32 of the blade. With the blade so engaged the user has only to grasp the outer end of the protective cover 31 and pull it toward the right thus stripping it from the 75 blade while the latter is held in shaving position.

tion. Having removed the cover in this manner the nut 14 may be rotated to lower the cap to its blade-clamping position, compressing the spring 25 and transversely flexing the blade into the desired condition for shaving.

Having thus disclosed my invention and described one illustrative embodiment thereof, I claim as new and desire to secure by Letters Patent:

1. A safety razor having cap and guard members connected for limited separation to receive a protected blade between them, one of said members having a pivotal mounting and carrying a projection for engaging a perforated blade, a spring for rocking said member to engage said projection with a blade, and separate means for rocking said member in opposition to the spring to disengage the blade.

2. A safety razor having cap and guard members connected for relative movement to clamp or release a perforated blade interposed between them, means for pivotally supporting one of said members, a projection at one side of said member for engaging said blade, and spring means acting at the other side of said member to rock it into blade-engaging position.

3. A safety razor having a convex blade-supporting member with a tubular handle, a spindle slidable in said handle and having a concave cap pivotally mounted at one end thereof, means for moving the spindle to release the cap, and means for yieldingly holding one end of the cap against said blade-supporting member.

4. A safety razor having a guard with a hollow handle, a cap with a spindle telescopically movable in said handle, said cap having a pivoted

stem located partially within said spindle and projecting on one side thereof, and a spring surrounding the spindle and bearing on one side of the stem whereby the cap is rocked into yielding engagement with an interposed blade.

5. A safety razor having a hollow handle with a guard fixed thereto, a cap having a blade-locating rib, a wider blade-engaging projection and a stem bevelled to a one-sided point, a spindle 10 sliding in said hollow handle, a spring surrounding the spindle and acting on the point of the stem to rock the cap in a manner carrying the blade-engaging projection thereof toward the said guard.

15. 6. A safety razor having a guard member, a central stem movable through the guard member, a cap member mounted to rock upon said stem and having on one face a projecting blade-locating rib and a projecting detent wider than 20 said rib, a spring tending to rock the detent of the cap toward the guard, and manual means for rocking the cap in the opposite direction.

7. A safety razor having cap and guard members connected for relative movement to clamp 25 or release an open-end blade interposed between them, means for pivotally mounting one of said members to rock with respect to the other member, and a blade-locating rib on one of said members having a projection at one end, the other 30 member being provided with a slot in which said projection may be received thereby providing an unbroken wall between the blade-engaging faces of the cap and guard which must be straddled by the two sides of the blade when presented 35 endwise between them.

NICHOLAS TESTI.
